ICE REFRIGERATOR

Charles F. Belshaw, Greenville, Mich.

Application January 9, 1936, Serial No. 58,361

8 Claims. (Cl. 62—31)

This invention relates to refrigerators and more particularly to refrigerators cooled by ice although some of its features may be utilized in mechanically cooled refrigerators.

5 Among the advantages of this invention are increased refrigerating efficiency, simplicity and cheapness of construction, minimizing moisture condensation on the outside front of the refrigerator, uniform air circulation in the provision 10 chamber, minimum condensation on interior surfaces, accessibility for cleaning, and maintenance of air circulation passages around the ice.

The invention provides various new and useful 15 features of construction and arrangement hereinafter more fully described and particularly pointed out in the claims, reference being had to the accompanying drawings, in which

Fig. 1 is a vertical sectional elevation, with parts 20 broken away, of an ice refrigerator embodying this invention shown in closed position.

Fig. 2 is a fragmentary sectional elevation of the front upper portion of the refrigerator showing both the outer door and the ice compartment gate opened.

25 Fig. 3 is a sectional plan view of the upper part of the refrigerator taken on the line 3—3 of Fig. 1.

Fig. 4 is a fragmentary sectional plan of the parts of Fig. 3 showing the ice compartment gate in lowered open position.

30 Fig. 5 is a fragmentary perspective view of one end of the ice compartment gate viewed from the rear or inner side.

Fig. 6 is a vertical sectional elevation on the line 6—6 of Fig. 1 of the upper part of the refrigerator.

35 Fig. 7 is a fragmentary perspective view of the inner part of the ice compartment and a portion of the ice supporting rack, and

Fig. 8 is a fragmentary perspective view from 40 the interior of a portion of a wing of the ice compartment gate and its engaging and retaining member.

Like numbers refer to like parts in all of the figures.

45 The refrigerator box proper comprises an outer casing 1 and an inner casing 2 spaced apart and having located between them conventional framework 3 and insulating material 4. Access to the interior of the refrigerator box is obtained, through the front and in the device illustrated, 50 a single door 5 is provided located in a door opening 6.

The ice chamber is located in the upper part 55 of the refrigerator and the provision chamber is that lower part of the interior of the refrigerator not occupied by the ice chamber. The ice chamber structure extends entirely across the interior of the refrigerator from one side to the other and is located against the back of the refrigerator 60 but is spaced from the front of the refrigerator

so that there is an appreciable opening between it and the outer door 5 when closed whereby the air circulation upward from the provision chamber passes between the ice chamber and the door before entering the ice chamber. 5

The ice chamber has a bottom pan 7 having upturned flanges at each of its sides and its side edges are supported by angle members 8 fastened directly to the sides of the inner casing 2 as by spot welding. The front edge of the bottom pan 7 is reinforced by a bar 9 of wood or similar heat insulating material, the ends of which are supported upon the angle members 8 and are preferably detachably connected thereto by means of screws 10. The sides and back of 15 the ice chamber are provided with an ice guard 11 which has outwardly turned flanges 12 at its top and bottom edges which space it from the inner casing 2 providing insulating dead air spaces at the sides and back of the ice chamber. 20

The ice rack 13 is made of relatively light weight sheet metal having deep corrugations extending its entire width from side to side of the ice chamber and the rack is supported by angle members 14 attached as by spot welding to the 25 respective sides of the ice guard 11 and inclined downwardly from front to rear, the supporting angles 14 having upwardly turned end portions 15, at front and rear to properly locate the ice rack thereon. An umbrella sheet 16 is located 30 against the bottom of the ice rack and is welded or otherwise attached to the downward corrugations thereof and this sheet serves to prevent spreading of the corrugations under heavy load as well as another purpose hereafter described. 35

The bottom pan 7 is inclined downwardly from front to rear and near its rear edge is provided with a drain spout 17 communicating with a drain pipe 18 which extends through the provision chamber and communicates with the drain 40 outlet 19 extending through the bottom of the refrigerator. Centrally spaced transversely of the bottom pan and nearer the back than the front thereof, but appreciably spaced from the back of the bottom pan and the refrigerator, is 45 provided a cold air flue 20 having an upwardly extending lip around its entire edge. The umbrella sheet 16 is located directly over the cold air flue 20 and serves the customary purpose of preventing moisture which may rise from the 50 provision chamber through the flue 20 directly contacting the ice rack 13 and condensing thereon.

The front of the ice chamber is provided with a gate 21 which is preferably formed of two 55 spaced metal sheets with insulation between them and this gate when closed is spaced from the front door 5, when it is closed, and the upper edge of the gate is spaced appreciably below the top of the refrigerator whereby an air passage 60

is provided from the provision chamber upwardly between the front door 5 and the front of the ice chamber and over the top of the gate into the ice chamber. The details of the construction 5 of the gate and its method of mounting and operation will be hereafter more fully described.

The structure so far describes results in various desirable functions. Inasmuch as there is no air passage between the provision chamber 10 and the ice chamber at the sides and back thereof of all of the warm air circulating from the provision chamber to the ice chamber must move to the front of the refrigerator and upwardly adjacent the back side of the front door 5 and thence over the top of the gate 21 into the ice 15 chamber. One desirable result of this air movement is that the warmest air in the refrigerator is brought adjacent the front door, where it is well recognized the greatest refrigeration loss 20 occurs. The result of this is that the heat differential between the outside of the refrigerator and the air immediately adjacent the front door is reduced which reduces the heat transfer at this location and increases the cooling efficiency 25 of the refrigerator and also minimizes the moisture condensation on the outside of the front of the refrigerator.

The deeply corrugated ice rack 13 provides a 30 stiff, strong member from relatively thin material which is of sufficient strength to support the ice 22 by supporting the rack only at its respective ends and without intermediate supports. This has the advantage of using a relatively light weight bottom pan 7 since this pan 35 does not support the load of the ice and furthermore, the elimination of the customary supporting legs intermediate the length of the rack eliminates the expense thereof and avoids rusting which ordinarily takes place when such legs 40 are used. Another advantage of this structure is that the weight of the ice is supported entirely at and by the respective sides of the chamber which load is carried, as will be seen, in Fig. 6, through the supporting angles 14, the lower 45 portion of the ice guard 11, and the supporting angles 8 which are attached directly to the sides of the inner casing 2.

Inasmuch as there are no perforations through 50 the ice rack 13, and the corrugations prevent the water from the melting ice flowing rearwardly, all of such water must run to and be drained from the respective ends of the rack from where it flows over the supporting angles 14, either rearwardly or down the sides of the ice guard 11 55 and thence flows along the rear edge of the bottom pan 7 into the drain spout 17. Thus none of this water, which is only slightly above freezing temperature, is deposited on the main body of the bottom pan 7 to cool it and cause condensation thereunder.

The crosswise corrugations in the ice rack 13 prevent the ice slipping rearwardly down the 60 inclination of the rack, as it would do if there were no such retaining means, and thus an air 65 passage space is maintained at the rear of the ice so that the air may always have free passage above, at the rear and at the front of the ice and may be most efficiently cooled thereby.

It is desirable to maintain a relatively thin 70 blanket of comparatively warm air at the back and at the sides of the provision chamber for insulation purposes and to this end the cold air flue 20 is located in a position spaced forwardly from the back of the refrigerator and also it is 75 centrally located in a crosswise direction and

the cold air moving downwardly through the flue does not engage either the sides or the back of the refrigerator but this flue is sufficiently near the back so that the cold air passing downwardly through it will circulate through the rear 5 part of the provision chamber without actually engaging the back wall thereof and will then move forwardly and upwardly as previously explained, and quite uniformly cool the provision chamber.

The supporting bar 9, past which the warm air from the provision chamber rises, being of wood or other non-conducting material, does not get extremely cold from the ice chamber and therefore does not condense moisture in the air 10 which moves past it, which condensation dripping into the provision chamber would be extremely objectionable.

The ice chamber gate 21 is mounted by novel 15 construction to swing without having a fixed hinge connection. This gate has inner and outer metal faces 25 between which is insulating material 26 which makes a rigid structure and insulates the passage between the gate and the door 5 from the ice chamber. The lower edge 20 of the gate is provided with a depending flange 27 along the lower front edge of the gate and an upwardly extending flange 28 at the front edge of the bottom pan 7 and above the supporting 25 rail 9 serves as a fulcrum on which the gate rests and swings. The gate is provided at its 30 respective ends with rearwardly extending wings 29 which have edges 30 in substantially the same plane as the lower edge of the gate and these edges 30 of the wings are turned outwardly and 35 return bent in the form of hooks 31.

When the gate is in vertical closed position its 40 ends overlap the respective front edges of the ice guard 11 and it cannot be moved backwardly sufficiently to slide off the flange 28 and in this position the wings 29 lie between the respective side members of the ice guard 11 and the sides of the inner casing 2 and the weight of these 45 wings tends to retain the gate in this upright closed position.

Retaining plates 32, with vertical hooked edges 33, are attached to the respective sides of the refrigerator with the hooked edges 33 extending 50 upwardly approximately above the supporting bar 9 and extending outwardly adjacent the wings 29 of the gate so that they will be engaged by the hooked edges 31 thereof.

When the gate is in vertical position the engagement of the flange 27 with the flange 28 prevents forward movement of the gate and the 55 front edges of ice guard 11, see Figs. 2 and 3, prevents rearward movement. When the gate is in lowered position the said co-acting pairs of hooked edges 21 and 33 engage to stop the downward movement of the gate in substantially horizontal position. Ears 34 at the upper ends of the hooked edges 33 overlap the upper ends of the hooked edges 31 when the gate is lowered and prevent its inner edge being raised but when the gate is swung upwardly a short distance the 65 upper ends of the hooked edges 31 will avoid the ears 34 and the gate may be raised upwardly sufficiently to gain access to the lower edge thereof and the flanges 27 and 28 for cleaning which accessibility is most desirable in a refrigerator.

This gate structure and means of mounting is simple to manufacture and assemble and is exceptionally strong which is necessary especially in its lowered position where it serves as a shelf 70 75

upon which the cake of ice is placed before moving it inward onto the ice rack and furthermore, when in this lowered position, the upper surface of the gate, including the flange 27 extending therefrom, extends inward and overlaps the forward edge of the bottom pan 7 so that anything deposited upon it, such as water or dirt from the ice, will find its way into the bottom pan when the gate is raised and cannot drop into the provision chamber. Another advantage of this gate extending entirely across the refrigerator door opening is that when it is lowered to receive ice it tends to conceal the provision chamber and its contents from the view of the ice delivery man.

From the foregoing it will be seen that many advantages are attained by this invention. The fact that all of the air which has been warmed in the provision chamber moves to the front and upwardly directly behind the outside door reduces the heat transfer from the outside to the inside of the refrigerator and increases the efficiency and minimizes the condensation on the exterior of the front of the refrigerator. The construction of the ice chamber and ice rack are simple and economical and strong. The fact that the bottom pan 7 supports no weight makes it possible to use thin metal in its construction. The ice rack, being deeply corrugated, is of sufficient strength to be supported entirely at its respective side edges which carries the weight of the ice upon it directly to the side structure of the refrigerator. The ice will not move backward down the incline of the ice rack because of the corrugations and thereby a free space is maintained for the circulation of air around the ice. The cold water drain from the ice is kept from the main body of the bottom pan so that it is not extremely cooled which eliminates condensation on the pan. The cold air, passing downwardly from the ice chamber, is kept from direct contact with the back and sides of the provision chamber so that a relatively warm air blanket may be maintained around the sides and back for heat insulation and the cold air passing into the provision chamber enters sufficiently near the back and thence moves downwardly and toward the front so that a substantially uniform cooling of the provision chamber is obtained. The supporting bar 9, past which the warmed air from the provision chamber moves, is of insulating material which prevents it getting extremely cold and eliminates condensation thereon. The gate structure is simple and rigid and provides an insulation at the front of the ice chamber as well as a simple swinging mounting and retaining means and accessibility for cleaning.

The ice cooling medium is spaced from all outside ice chamber walls and protected from radiant heat therefrom on all sides by the U-shaped ice guard and its front enclosing insulated gate all of which are finished in heat reflective coatings to act as effective heat radiation shields.

The invention is defined in the appended claims and is to be considered comprehensive of all forms of structure coming within their scope.

I claim:

1. A refrigerator having a provision chamber, an opening leading thereto, a door for said opening and an ice chamber structure in said provision chamber, said ice chamber structure extending entirely across the provision chamber from side to side near the top thereof and located against the back of said provision chamber

and spaced from the inner side of said front door and having an airentrance passage at its front upper portion and having a cold air flue through its lower side.

2. The elements in combination defined in 5 claim 1, in which said ice chamber structure is provided with a heat insulated door spaced from the inner side of said outer door and accessible through said outer door opening.

3. The elements in combination defined in 10 claim 1, in which the forward lower edge of said ice chamber structure is heat insulated from the interior thereof.

4. In a refrigerator having a provision chamber, an ice chamber located above the provision 15 chamber, an inclined bottom pan separating said ice chamber from said provision chamber, an ice rack spaced from said bottom pan and having no supporting means in engagement with said bottom pan excepting at the extreme edges thereof and means for carrying all water from melting ice on said rack to the side edges of said inclined bottom pan.

5. In a refrigerator having a provision chamber, an ice chamber located above the provision 25 chamber, a bottom pan inclined from front to rear separating said ice chamber from said provision chamber, an ice rack located above and spaced from said bottom pan, said ice rack also being inclined from the front to the rear of said 30 ice chamber and having corrugations extending transversely of said ice chamber, means for supporting said ice rack entirely at its respective ends and out of contact with the main body portion of said bottom pan, and said ice rack being imperforate, whereby all water melted from ice thereon drains from its end or ends to the side edge or 35 edges of said inclined bottom pan.

6. In a refrigerator having a gate, means for swingably mounting the gate whereby it may be 40 swung to closed and open positions and also be lifted from its pivot, and means for preventing lifting movement when the gate is swung to a certain predetermined operating position said last mentioned means being spaced from the 45 pivot.

7. The combination of elements as set forth in claim 6 but also having means for limiting the swinging movement of the gate to open position, said means also acting to carry the center of 50 gravity of said gate rearwardly of its point of support, as the gate approaches its closed position, to urge the gate toward and to maintain the gate in closed position.

8. In a refrigerator, an ice chamber therein 55 having an open front side, a gate to partially close said front opening, a downwardly extending flange at the lower edge of said gate, means in the lower edge of said front opening loosely engaging the lower edge of said gate forwardly of 60 said flange, means for preventing rearward movement of said gate when in vertical position sufficient to dislodge its lower edge from said means at the lower edge of the opening, means for limiting the outward and downward swinging movement of said gate, and means for preventing the upward movement of the inner edge of said gate when in open position, said last mentioned means being inoperative when said gate is in any other position whereby the lower edge of the gate may 65 be lifted from its supporting means.

CHARLES F. BELSHAW.
